CLAIM

The ornamental design for a skin treatment device, as shown and described.

DESCRIPTION

FIG. 1 is a front perspective view of a skin treatment device showing a first embodiment of our new design;

FIG. 2 is a right side view thereof;

FIG. 3 is a left side view thereof;

FIG. 4 is a front view thereof;

FIG. 5 is a rear view thereof;

FIG. 6 is a top plan view thereof;

FIG. 7 is a bottom view thereof;

FIG. 8 is a front perspective view of a second embodiment of a skin treatment device showing our new design;

FIG. 9 is a right side view thereof;

FIG. 10 is a left side view thereof;

FIG. 11 is a front view thereof;

FIG. 12 is a rear view thereof;

FIG. 13 is a top plan view thereof;

FIG. 14 is a bottom view thereof;

FIG. 15 is a front perspective view of a third embodiment of a skin treatment device showing our new design;

FIG. 16 is a right side view thereof;

FIG. 17 is a left side view thereof;

FIG. 18 is a front view thereof;

FIG. 19 is a rear view thereof;

FIG. 20 is a top plan view thereof; and,

FIG. 21 is a bottom view thereof.

The broken lines in the drawings are for the purpose of illustrating portions of the skin treatment device which form no part of the claimed design.
